UNITED STATES PATENT OFFICE.

ALBERT B. HERRICK, OF RIDGEWOOD, NEW JERSEY, ASSIGNOR TO THE ELECTRIC RAILWAY IMPROVEMENT COMPANY, OF CLEVELAND, OHIO, A CORPORATION OF OHIO.

APPARATUS FOR MAKING RAIL-BONDS.

No. 870,169.

Specification of Letters Patent.

Patented Nov. 5, 1907.

Application filed May 5, 1904. Serial No. 206,496.

To all whom it may concern:

Be it known that I, ALBERT B. HERRICK, a citizen of the United States, and a resident of Ridgewood, county of Bergen, and State of New Jersey, have invented a new and useful Improvement in Apparatus for Manufacturing Rail-Bonds, of which the following is a specification, the principle of the invention being herein explained and the best mode in which I have contemplated applying that principle so as to distinguish it from other inventions.

My invention relates to apparatus for manufacturing rail-bonds, and particularly to a block about which a conductor is adapted to be wound to form such bonds.

Said invention consists of means hereinafter fully described and specifically pointed out in the claims.

The annexed drawings and the following description set forth in detail certain means embodying the invention, such disclosed means constituting but one of various mechanical forms in which the principle of the invention may be used.

In said annexed drawings:—Figure 1 represents a perspective view of the improved forming block used in my invention; Fig. 2 represents the same with a conductor wound around it, and flux applied to some parts of such conductor; Fig. 3 represents the same as Fig. 2 with transverse strips or terminals clamped over the parts of said conductor to which the flux has been applied; Fig. 4 represents a perspective view of the conductor removed from the block, and sawed into two similar parts; Fig. 5 represents an end view of a transverse vertical section through the conductor, transverse strip and intermediate flux; Fig. 6 represents a front view of mechanism adapted to utilize said block for manufacturing the bonds shown in Fig. 4; and Fig. 7 represents a side elevation of such mechanism.

The improved block used in my invention consists of a base A provided with a raised surface or boss a, both of any desired shape or outline, and being shown as elliptical in the form of device illustrated. Said block is intersected by a transverse slot or fissure a³ which cuts completely through the boss a and for some distance into the base A, and, in the device shown, passes through the center of the block, thus dividing the boss a into two similar parts. A small notch a² is provided in the boss a, and the latter is cut away on both of its sides for a small space as shown at a', said spaces intersecting the plane of the outer or main surface of the boss the purpose of which notch a² and cut-away portions a' will be hereinafter fully explained. Said improved block is utilized by winding a conductor around the boss a to form a plurality of rail-bonds, and, after said conductor is provided with flux in certain parts and with transverse strips or ter-

minals, it is cut or separated into the individual bonds. Figs. 6 and 7 represent apparatus for so utilizing the block, and the method of operation will now be set forth.

The block is attached in any suitable manner to a shaft d operated from a shaft e, and a suitable clutch f enables the block to be thrown into operative relation with the shaft d. A suitable conductor C, Figs. 2 and 3, is attached at one end to the boss a, being secured in the notch a², and by the rotation of the block any desired quantity of the conductor may be wound in convolutions around the boss a. A quantity of flux a⁴ is then spread over the wound conductor C transversely of the slot a³ and for some distance on either side of the same, as shown. The block is then placed under a suitable press or die G operated from a shaft g connected with the shaft e, as shown, and transverse strips a⁵, or what serve as terminals in the finished bond, are securely fastened over the flux portions, one side of such strips a⁵ being secured in the cut-away portions a', and the other side about the outer strip B of the conductor C. The block is then fastened in a suitable casing H and the conductor C is cut into two similar bonds c and c' by means of a saw J operated from the shaft e, such cut being made through the strips a⁵ and the flux a⁴, there being space provided for the operation of the saw J in the slot a³. The end b of the conductor C that has been retained in the notch a² is then pressed back against the inner periphery of the bond c, and the two similar bonds are complete.

It is obvious that the described improved block can be utilized to manufacture more than two bonds at one operation by sawing the wound conductor into three or more parts; that said parts or the finished bonds may not necessarily be similar or of the same size; and that a block of an outline other than elliptical may be used.

Other modes of applying the principle of my invention may be employed instead of the one explained, change being made as regards the means herein disclosed provided the means stated by any one of the following claims or the equivalent of such stated means be employed.

I therefore particularly point out and distinctly claim as my invention:—

1. In apparatus for manufacturing rail-bonds, a block provided with a raised surface about which a conductor is adapted to be wound and with slots dividing said surface into a plurality of parts.

2. In apparatus for manufacturing rail-bonds, a block provided with a raised surface of an outline similar to the combined outline of two of said bonds about which a conductor is adapted to be wound and a transverse slot dividing said surface into two similar parts.

3. In apparatus for manufacturing rail-bonds, a block provided with a raised boss of an outline similar to that of the bond and around which the latter may be formed,

said boss having two oppositely disposed spaces cut into its sides.

4. In apparatus for manufacturing rail-bonds, a block provided with a raised boss of an outline similar to that of the bond and around which the latter may be formed, said boss having two oppositely disposed spaces cut in its sides, said spaces intersecting the plane of the outer or main surface of the boss.

5. In apparatus for manufacturing rail-bonds, a block provided with a raised surface about which a conductor is adapted to be wound and with slots dividing said surface into a plurality of parts, said raised surface having spaces cut into its sides at points adjacent to said slots.

6. In apparatus for manufacturing rail-bonds, a block provided with a raised boss, of an outline similar to the combined outlines of two of said bonds, about which a conductor is adapted to be wound, and a transverse slot dividing said boss into two similar parts, said boss having

spaces cut into its sides at the points of their intersection by said slot.

7. In apparatus for manufacturing rail-bonds, a block provided with a raised boss of substantially elliptical outline about which a conductor is adapted to be wound, and a transverse slot dividing said boss into two similar parts.

8. In apparatus for manufacturing rail-bonds, a block provided with a raised boss of substantially elliptical outline about which a conductor is adapted to be wound, and a transverse slot dividing said boss into two similar parts, said boss having spaces cut into its sides at the point of their intersection by said slot.

Signed by me, this 2nd day of May 1904.

ALBERT B. HERRICK.
